UNITED STATES PATENT OFFICE.

JOHN F. STONER, OF STARK COUNTY, OHIO.

COMBINED RAILWAY-TIE AND RAIL-FASTENER.

No. 888,670.

Specification of Letters Patent.

Patented May 26, 1908.

Application filed January 17, 1908. Serial No. 411,242.

To all whom it may concern:

Be it known that I, JOHN F. STONER, a citizen of the United States, residing in Stark county, near the village of Dalton, 5 Wayne county, State of Ohio, have invented certain new and useful Improvements in a Combined Railway-Tie and Rail-Fastener; and I do hereby declare that the following is a full, clear, and exact description of the 10 same, reference being had to the accompanying drawing, making a part of this specification, and to the numerals and figures of reference marked thereon, in which—

Figure 1 is a perspective view showing the 15 different parts in relative position. Fig. 2 is a view showing a portion of the tie in transverse section illustrating a single rail locking spike or dog showing the locking lever elevated and the locking plate in position before the spike or dog is locked. Fig. 3 is a similar view showing two spikes or dogs located side by side. Fig. 4 is a detached view of a spike or dog. Fig. 5 is a detached view of a locking plate designed 25 to lock one spike or dog. Fig. 6 is a detached view of the locking plate designed to lock or hold two spikes or dogs. Fig. 7 is an end view of the tie showing a rail located thereon and illustrating the locking plate 30 and lever brought into position to lock the spike or dog.

The present invention has relation to combined railway tie and rail fasteners and it consists in the parts and combination of 35 parts hereinafter described and pointed out in the claims.

Similar numerals of reference indicate corresponding parts in all the figures of the drawing.

40 In the accompanying drawing, 1 represents the web of the tie, which web is provided with the integral base flange 2 and the rail flange 3. The rail flange 3 is provided with the integral rail holding lugs 4, which are 45 located a distance apart equal to the distance between the outer edges of the two railway rail bases 5. The integral rail holding lugs 4 are so formed that they will assist in retaining the railway rails in proper position with reference to each other and assist in holding the railway rails in contact with the top of the flange 3. Below the flange 3 are located the locking plates 6 and 7, which locking plates are substantially of the form 55 shown in Figs. 5 and 6, and are located through suitable apertures 8 formed in the

web 1 and just below the rail supporting flange 3. The spikes or dogs 9 are substantially of the form shown and are provided with the usual rail flange holding heads. 60 The spikes or dogs are each provided with the narrowed portion 10, which narrowed portion is formed of a thickness equal to the smaller openings 11 formed in the locking plates 6 and 7. The locking plates 6 and 7 are also provided with the larger openings 12. The larger openings 12 are for the purpose of allowing the lower headed ends 13 of the spikes 9 to be passed through said openings so that the dogs or spikes can be 70 placed in the position illustrated in Figs. 1, 2 and 3.

The locking plates 6 and 7 are each provided with the hooked ends 14, which hooked ends are for the purpose of receiving the 75 cross-bars 15, located upon or through the cam heads 16, which cam heads are formed integral with the locking levers 17. In use the rails are placed in proper position upon the tie or ties. The spikes or locking dogs 9 80 are passed through the apertures 18 in the tie and the larger openings 12, after which the locking levers 17 are brought into the position shown in Fig. 7.

It will be understood that as the locking 85 levers are brought from a horizontal position into a substantially vertical position the locking plates 6 and 7 will be moved endwise thereby bringing the smaller opening 11 into engagement with the narrowed portions 10 90 and locking the spikes in fixed position.

It will be understood that during the time the locking levers are moved downward their cam ends will bear against the adjacent spike 9 when two spikes are used as illustrated in 95 Fig. 3 and against the web 1 of the tie when a single spike is used as illustrated in Fig. 2, thereby providing suitable bearing surfaces for the cam heads 16.

It will be understood that after the levers 100 17 are brought into lowered positions the usual ballast is placed between the ties, which prevents the levers from becoming accidentally displaced and also prevents any accidental displacement of the locking levers 105 6 or 7 as the case may be.

For the purpose of assisting in holding the locking levers in proper position to lock the locking plates and spikes or dogs their free ends are provided with weights 19, which 110 weights assist in holding the locking levers in a vertical position as illustrated in Fig. 7.

Having fully described my invention what I claim as new and desire to secure by Letters Patent, is—

1. In a railway tie and fastener, the combination of a railway tie provided with fixed rail-holding lugs, locking plates provided with openings of different sizes and hooked ends, locking levers provided with cam heads and bars adapted to engage the hooked ends 10 of the locking plate and spikes or dogs adapted to be locked by the locking plates, substantially as and for the purpose specified.
2. In a railway tie and fastener, the combination of a railway tie provided with fixed 15 rail-holding lugs, locking plates provided

with openings of different sizes and hooked ends, locking levers provided with cam heads at one end and weighted portions at the other end and bars adapted to engage the hooked ends of the locking plate, and spikes or dogs 20 adapted to be locked by the locking plates, substantially as and for the purpose specified.

In testimony that I claim the above, I have hereunto subscribed my name in the presence of two witnesses.

JOHN F. STONER.
